PORTABLE LITTER RECEPTACLES
Rudolph J. Lukezich, 1121 N. Maple St.,
Royal Oak, Mich.
Filed June 21, 1963, Ser. No. 290,882
15 Claims. (Cl. 15—142)

The present application is a continuation-in-part of my copending application Serial No. 202,198, filed June 13, 1962 and now abandoned.

The present invention relates to litter receptacles and more particularly to such a device adapted for use in combination with what are commonly called "dry" mops.

Presently a large portion of the every day cleaning of the floors of buildings and institutions such as office buildings, schools and the like, is being done with what are referred to as "dry" mops. These are essentially standard dust mops which have been impregnated with a cleaning compound. Dust and debris will adhere to such a mop and it is therefore necessary to periodically remove this matter to restore the mop to effective working condition.

It is an object of the present invention to provide a means of removing and collecting matter adhering to "dry" type mops and the like by providing a receptacle having an overlying grate member over which such a mop may be agitated.

It is yet another object of the present invention to reduce the time and difficulty of cleaning floors and the like by providing a litter receptacle which may be readily moved about and which is provided with ramp means upon which dirt and refuse may be swept or mopped into the receptacle.

It is still another object of the present invention to ease the cleaning of dry type mops and the like by providing a portable litter receptacle having means selectively operable to lock the device in a stationary position with respect to the floor.

It is still another object of the present invention to reduce shipping costs and storage space for the aforementioned receptacles by providing a device which folds up into a compact unit.

It is yet another object of the present invention to increase the maneuverability of litter receptacles and the like by providing a steering post rotatably mounted on the front of such a device, a wheel member mounted on each side of said post and an elongated handle connected with the opposite end of the steering post.

It is still a further object of the present invention to provide such a device having a readily removable refuse collecting liner.

Still further objects and advantages will readily occur to one skilled in the art to which the invention pertains upon reference to the following drawings in which like reference characters refer to like parts throughout the several views and in which

FIG. 1 is an exploded perspective view of one preferred embodiment of the present invention.

FIG. 2 is a fragmentary perspective view enlarged for purposes of clarity and as seen from the right hand side of FIG. 1.

FIG. 3 is a fragmentary perspective view as seen from the left hand side of FIG. 1.

FIG. 4 is an exploded perspective view of another preferred embodiment of the present invention.

FIG. 5 is a fragmentary perspective view of the embodiment shown in FIG. 4 and illustrating the device in use, and

FIG. 6 is a front elevational view of the embodiment shown in FIG. 4 illustrating the device in the folded or compact position.

Now referring to the drawings for a more detailed de-

2

scription of the present invention, one preferred device is illustrated in FIGS. 1-3 as comprising a housing 10 having a pair of substantially vertical side walls 11 and end walls 12 and a substantially horizontal floor portion 13. The walls 11-12 and floor portion 13 define a reception chamber 14. The end walls 12 preferably are provided with top flanges 15 which diverge outwardly of the housing 10 in a common plane substantially parallel to the plane of the floor portion 13 while the side walls 11 are provided with top flanges 16 which diverge outwardly and upwardly with respect to the housing 10.

A grate member 17 is adapted to be removably carried by the housing 10 in a position substantially parallel to and overlying the floor portion 13 and for this purpose has edge portions 18 which are bent complementary to the top flange 16. Resilient seat members 19 are provided to engage the surface of the flanges 16. Longitudinal bars 17A have return bent ends adapted to engage the inner surfaces of the end walls 12 of the housing 10 to limit longitudinal movement of the grate member 17.

A removable insert pan 20 is adapted to be carried in the reception chamber 14 intermediate the grate member 17 and the floor portion 13. A laterally extending bar-shaped handle 20A is provided for the insert pan 20.

A ramp member 21 having a planar surface 21a is hinged as at 23 to one of the flanges 16.

As can best be seen in FIGS. 1 and 2, the exterior surface of the floor portion 13 is preferably provided with a plurality of resilient support members 24. An angle member 25 is carried on the exterior surface of one of the end walls 12 intermediate the floor portion 13 and the top flange 15 by a pair of hinge members 26. The hinge members 26 permit the angle member 25 to pivot in a plane substantially normal to the plane of the floor portion 13 as indicated by the dotted line position of FIG. 2. An arm member 27 pivotally carries a latch member 28. A spring 29 urges the latch member 28 to engage the angle member 25 and prevent pivotal movement thereof. Pivoting of the latch member 28 away from the angle member 25 permits the latter to pivot and a cam surface 30 of the latch member 28 prevents the return of the angle member 25 to the solid line position until once again the latch member 28 has been pivoted, preferably by manually depressing a flange 28A provided for this purpose.

A bar 31 is secured to the angle member 25 by any convenient means such as welding (not shown) and rotatably carries a steering post 32. The steering post 32 rotates on an axis substantially normal to the plane of the floor portion 13 and has an end extending closely adjacent the plane of the flange 15 and an opposite end extending closely adjacent the plane of the floor portion 13. A cross shaft 32A is carried at the lower end of the steering post 32. Wheels 33 are rotatably carried at opposite ends of the cross shaft 32A, and a handle 34 is pivotally mounted on the opposite end of the steering post 32.

A pair of hinges 35 is carried on the exterior surface of the floor portion 13 closely adjacent the other end wall 12 and are operable to pivot a rod 36 from the solid line position illustrated in FIG. 3 in a plane substantially normal to the plane of the floor portion 13 to the dotted line position illustrated in FIG. 3. The rod 36 rotatably carries a pair of wheel 37.

It is apparent that the present device has been designed to permit it to be readily stored until it is ready for use. The handle 34 will pivot to a position resting on the grate 17 and the ramp 21 will pivot to a position overlying the handle 34. When it is desired to use the device, the wheels 33-37 are positioned in the solid line positions illustrated and the handle 34 is used to pull the device to the location where it is to be used. The wheels 33 being swivelingly mounted to the bar 31 by the steering post

32 permits the device to be maneuvered easily. When the location of use has been reached, the ramp 21 is moved so that its bottom edge engages the floor and refuse may then be swept up the ramp 21 and into the removable pan 20. When the mop becomes clogged with dirt the wheels 33-37 are pivoted to the dotted line positions indicated and the device will then rest on the resilient supports 24. These will resist relative movement between the device and the floor and the mop may then be agitated across the top of the grate 17 to loosen the dirt and refuse adhering to the mop and thus restore it to working condition.

Another preferred embodiment of the present invention is illustrated in FIGS. 4-6 as comprising a housing 110 substantially similar to the housing 10 described above and having a pair of substantially vertical side walls 111 and end walls 112 and a substantially horizontal floor portion 113. The walls 111-112 and floor portion 113 define a reception chamber 114. The end walls 112 preferably are provided with top flanges 115 which diverge outwardly of the housing 110 in a common plane and substantially parallel to the plane of the floor portion 113 while the side walls 111 are provided with top flanges 116 which diverge outwardly and upwardly with respect to the housing 110.

A grate member 117 substantially similar to the grate member 17 described above is adapted to be removably carried by the housing 110 in a position substantially parallel to and overlying the floor portion 113. Edge portions 118 and seat members 119 engage the surface of the flanges 116 to position the grate member 117 as described above with reference to FIGS. 1-3. Longitudinal bars 117A have return bent ends which engage the inner surfaces of the end walls 112 to limit longitudinal movement of the grate member 117.

It will be noted that the insert pan 20 of the embodiment illustrated in FIGS. 1-3 is not used with the embodiment shown in FIGS. 4-6.

A ramp member 121 is provided with a planar surface 121A and is hinged as at 123 to one of the flanges 116 and is adapted to be pivoted from the position shown in FIG. 4 to the position covering the device as illustrated in FIG. 6.

An angle member 125 is secured to the exterior surface of one of the end walls 112 preferably by welding (not shown). A hollow bar 131 is secured to the angle member 125 by any convenient means such as welding (not shown) and rotatably carries a steering post 132. As can best be seen in FIG. 6, the steering post 132 rotates on an axis substantially normal to the plane of the floor portion 113 and has one end 113A extending closely adjacent the plane of the flange 115 and an opposite end 113B extending closely adjacent the plane of the floor portion 113.

A cross shaft 132A is carried adjacent the end 113B of the steering post 132 and rotatably carries a pair of wheels 133. The wheels 133 are positioned on opposite sides of the post 132 and closely adjacent thereto and are preferably rotatable on axes closely adjacent the plane of the floor portion 113.

The end 113A of steering post 132 carries a cross pin 132A. An elongated handle 134 is pivotally mounted to the post 132 by brackets 135. The handle 134 pivots on an axis closely adjacent the plane of the top flange 115. The handle 134 is preferably provided with a pair of rubber grips 138.

As can best be seen in FIG. 6, a rod 136 is secured to the exterior surface of the floor portion 113 and rotatably carries a pair of wheels 137.

The preferred embodiment illustrated in FIGS. 4-6 is shown in FIG. 5 in position to be used to clean a mop (not shown). The handle 134 is pivoted downwardly until the grips 138 engage the floor. The operator steps on the grips 138 to prevent the device from moving while the mop is agitated across the grate 118.

FIG. 6 illustrates the preferred embodiment in a folded or compact position for storage or shipping. The handle 134 will pivot downwardly to rest upon the grate member 117 and the ramp member 121 will pivot over the handle 134 to close the top of the device. While it has been preferred to illustrate only the preferred embodiment of FIGS. 4-6 in the folded or compact position, it is apparent that the embodiment of FIGS. 1-3 can be similarly positioned.

Preferably the wheels 133 and 137 are constructed of rubber or similar material so that when litter is being swept up the ramp member 121 the wheels 133 and 137 will resist displacement of the device.

The particular construction and positioning of the steering posts 32 and 132, the wheel members 33 and 133 and the wheel members 37 and 137 described in detail with respect to the embodiment illustrated in FIGS. 4-6 provides a device which may be easily maneuvered from place to place. In addition, by positioning the axis of the wheels 33, 133, 37 and 137 substantially parallel with and closely adjacent the floor portions 13 and 113 respectively the floor portions 13 and 113 are positioned closely adjacent the floor being cleaned. This permits a ramp to be provided to the top of the device and without requiring an angle which would make mopping up the ramp difficult.

The flange portions 16 and 116 provide the means by which the grate members 17 and 117 respectively are retained in position during use and by which the grate members 17 and 117 may be readily removed when the device becomes full of litter and requires emptying. In addition, the flange portions 16 and 116 also position the ramp member 21 and 121 from the grate members 17 and 117 when the device is folded so that a space is provided for the handles 34 and 134.

It is apparent that although it has been preferred to describe the embodiment of FIGS. 1-3 as including an insert pan 20 that the device could also be used without it. Similarly, although it has been preferred to describe the embodiment of FIGS. 4-6 as not including such a pan, it could also be used with that device.

Although I have described two embodiments of the present invention, it is apparent that other changes and modifications may be made without departing from the spirit of the invention or the scope of the appended claims.

I claim:

1. A device for the reception of litter and the like comprising
  - (a) a housing having substantially vertical side and end walls and a substantially horizontal floor portion, said walls defining an open top reception chamber,
  - (b) a grate member removably carried by said walls in a position substantially parallel to and overlying said floor portion,
  - (c) a removable insert pan carried in said reception chamber intermediate said grate member and said floor portion,
  - (d) said insert pan being vertically removable from said reception chamber and having handle means for manually lifting said pan from said reception chamber,
  - (e) wheel members carried by and supporting said housing,
  - (f) means for selectively pivoting said wheel members upwardly in planes substantially normal to the plane of said floor portion to a pivotal position,
  - (g) means swivelingly mounting a pair of said wheel members to said pivoting means whereby said pair of wheel members may be swiveled in a plane substantially parallel to the plane of said floor portion,
  - (h) a handle member pivotally connected to said pair of wheel members, and
  - (i) a ramp member and means hingedly connecting

- said ramp member to the top edge of one of said walls.
2. A device for the reception of litter and the like comprising
- (a) a housing having substantially vertical side and end walls and a substantially horizontal floor portion, said walls defining an open top reception chamber, 5
  - (b) a grate member removably carried by said walls in a position substantially parallel to and overlying said floor portion, 10
  - (c) wheel members carried by and supporting said housing,
  - (d) means for selectively pivoting said wheel members upwardly in planes substantially normal to the plane of said floor portion to a pivotal position, 15
  - (e) means swivelingly mounting a pair of said wheel members to said pivoting means whereby said pair of wheel members may be swiveled in a plane substantially parallel to the plane of said floor portion, 20
  - (f) a handle member pivotally connected to said pair of wheel members, and
  - (g) a ramp member and means hingedly connecting said ramp member to the top edge of one of said walls. 25
3. A device for the reception of litter and the like comprising
- (a) a housing having substantially vertical side and end walls and a substantially horizontal floor portion, said walls and floor portion defining an open top reception chamber, 30
  - (b) a grate member removably carried by said walls in a position substantially parallel to and overlying said floor portion,
  - (c) a removable insert pan carried in said reception chamber intermediate said grate member and said floor portion, 35
  - (d) said insert pan being vertically removable from said reception chamber and having handle means for manually lifting said insert pan from said reception chamber, 40
  - (e) a first and second pair of wheel members carried by and supporting said housing,
  - (f) said walls having a top flange,
  - (g) a ramp member having a top edge hingedly connected to the top flange of one of said walls and a second edge substantially normal to said top edge, 45
  - (h) said second edge having a length greater than the height of said walls,
  - (i) means for selectively pivoting said first and second pair of wheel members upwardly in planes substantially normal to the plane of said floor portion to a pivotal position, said means comprising an angle member hingedly carried on the exterior surface of one of said end walls and operable 50
  - to be pivoted upwardly to a pivoted position, a latch member selectively operable to prevent movement of said angle member to said pivoted position, and
  - said first pair of wheel members being rotatably carried by said angle members and pivotal therewith, hinge means carried on the other end wall and having means for rotatably carrying said second pair of wheel members, 55
  - (j) means swivelingly mounting said first pair of said wheel members to said pivoting means whereby said first pair of wheel members may be swiveled in a plane substantially parallel to the plane of said floor portion, and
  - (k) a handle member pivotally connected to said first pair of wheel members. 70
4. A device for the reception of litter and the like comprising
- (a) a housing having substantially vertical side and end walls and a substantially horizontal floor portion, 75

- said walls and floor portion defining an open top reception chamber,
- (b) a grate member removably carried by said walls in a position substantially parallel to and overlying said floor portion,
  - (c) wheel members carried by and supporting said housing,
  - (d) a ramp member having a top edge hingedly connected to the top flange of one of said walls and a second edge substantially normal to said top edge,
  - (e) said second edge having a length greater than the height of said walls,
  - (f) means for selectively pivoting said wheel members upwardly in planes substantially normal to the plane of said floor portion to a pivotal position, said means comprising an angle member hingedly carried on the exterior surface of one of said end walls and operable to be pivoted upwardly to a pivoted position, a latch member selectively operable to prevent movement of said angle member to said pivoted position, and
  - at least one of said wheel members being rotatably carried by said angle member and pivotal therewith,
  - means pivotally carried on the other end wall and having means for rotatably carrying a pair of said wheel members,
  - (g) means swivelingly mounting said angle member carried wheel member to said angle member whereby said wheel member may be swiveled in a plane substantially parallel to the plane of said floor portion, and
  - (h) a handle member pivotally connected to said angle member carried wheel member.
5. A device for the reception of litter and the like comprising
- (a) a housing having substantially vertical side and end walls and a substantially horizontal floor portion, said walls defining an open top reception chamber,
  - (b) a grate member removably carried by said walls in a position substantially parallel to and overlying said floor portion,
  - (c) a removable insert pan carried in said reception chamber intermediate said grate member and said floor portion,
  - (d) said insert pan being vertically removable from said reception chamber and having handle means for manually lifting said insert pan from said reception chamber,
  - (e) a first and a second pair of wheel members carried by and supporting said housing,
  - (f) said walls having a top flange,
  - (g) a ramp member having a planar surface,
  - (h) one edge of said planar surface hingedly connected to the top edge of one of said walls and a second edge of said planar surface being substantially normal to said top edge,
  - (i) said second edge having a length greater than the height of said walls whereby said ramp member is operable to pivot to a floor engaging position and said planar surface provides a surface in said pivoted position upon which litter can be swept from the floor into said insert pan, and
  - (j) means for selectively pivoting said pairs of wheel members upwardly in planes substantially normal to the plane of said floor portion to a pivotal position, said means comprising an angle member hingedly carried on the exterior surface of one of said end walls and operable to pivot upwardly to a pivoted position, a latch member selectively operable to prevent movement of said angle member to said pivoted position,

said first pair of wheel members being rotatably carried by said angle member and pivotal therewith, a hinge member carried on the other end wall and having means for rotatably carrying said second pair of wheel members.

6. The device as defined in claim 5 and including means swivelingly mounting said first pair of said wheel members to said angle member whereby said first pair of wheel members may be swiveled in a plane substantially parallel to the plane of said floor portion.

7. A device for the reception of litter and the like comprising

- (a) a housing having substantially vertical side and end walls and a substantially horizontal floor portion, said walls defining an open top reception chamber, 15
- (b) a grate member removably carried by said walls in a position substantially parallel to and overlying said floor portion,
- (c) a first and second pair of wheel members carried by and supporting said housing, 20
- (d) said walls having a top flange,
- (e) a ramp member having a planar surface,
- (f) one edge of said planar surface hingedly connected to the top edge of one of said walls and a second edge of said planar surface being substantially 25 normal to said top edge,
- (g) said second edge having a length greater than the height of said walls whereby said ramp member is operable to pivot to a floor engaging position and said planar surface provides a surface in said pivoted 30 position upon which litter can be swept from the floor into said reception chamber, and
- (h) means for selectively pivoting said wheel members upwardly in planes substantially normal to the plane of said floor portion to a pivotal position, 35 said means comprising an angle member hingedly carried on the exterior surface of one of said end walls and operable to pivot upwardly to a pivotal position, a latch member selectively operable to prevent 40 movement of said angle member to said pivotal position, said first pair of wheel members being rotatably carried by said angle member and pivotal therewith, hinge means carried on the other end 45 wall and having means rotatably carrying said second pair of wheel members.

8. The device as defined in claim 7 and including means swivelingly mounting said first pair of said wheel members to said pivoting means whereby said first pair of wheel members may be swiveled in a plane substantially parallel to the plane of said floor portion.

9. A device for the reception of litter and the like comprising,

- (a) a housing having a floor portion and defining an open top reception chamber, 55
- (b) a grate removably carried by said housing in a position substantially parallel to and overlying said floor portion,
- (c) wheel members carried by and supporting said housing,
- (d) a ramp member having an edge hingedly connected to said housing,
- (e) means for selectively pivoting said wheel members upwardly in planes substantially normal to the plane of said floor portion to a pivotal position, and 60
- (f) means swivelingly mounting a pair of said wheel members to said pivoting means whereby said pair of wheel members may be swiveled in a plane substantially parallel to the plane of said floor portion.

10. A device for the reception of litter and the like comprising

- (a) a housing having a floor portion and defining an open top reception chamber,

- (b) a grate member carried by said housing in a position overlying said floor portion,
- (c) a ramp member having an edge hingedly connected to said housing,
- (d) a horizontal rod secured to the exterior of said floor portion near one end of said housing and a wheel rotatably mounted on each end of said rod,
- (e) a bracket mounted on the exterior surface at the other end of said housing in a position spaced upwardly from said floor portion,
- (f) a post rotatably mounted in said bracket to rotate on an axis substantially normal to the plane of said floor portion,
- (g) a cross shaft mounted in said post and having an axis substantially co-planar with the plane of said floor portion,
- (h) a wheel member rotatably mounted on each end of said cross shaft whereby said last mentioned wheel members are substantially coaxial with said rod mounted wheel members, and
- (i) a handle member pivotally connected with said post.

11. A device for receiving litter from a floor or the like comprising

- (a) a housing having substantially vertical side and end walls and a substantially horizontal floor portion,
- (b) said walls and said floor portion defining an open top reception chamber,
- (c) a grate member carried by said walls in a position overlying said floor portion,
- (d) a ramp member and means pivotally connecting said ramp member with said housing on an axis substantially parallel with said floor portion,
- (e) said ramp member being operable to pivot from a floor engaging position to a position closing the top of said open top reception chamber,
- (f) a pair of rear wheel members rotatably carried by and supporting said housing,
- (g) a steering post rotatably mounted to said housing to rotate in an axis substantially normal to the plane of said floor portion,
- (h) a pair of front wheel members each rotatably mounted on one end of said steering post,
- (i) a handle connected with the opposite end of said post and being operable to pivot to a position overlying said grate member whereby said device can be folded into a compact position by pivoting said handle over said grate member and pivoting said ramp member over said handle.

12. A device adapted to receive litter from a floor and the like comprising

- (a) a housing having substantially vertical side and end walls and a substantially horizontal floor portion,
- (b) said walls and said floor portion defining an open top reception chamber,
- (c) each of said side walls being provided with a top flange extending angularly upwardly and outwardly from said housing,
- (d) a grate member removably carried by said top flanges in a position overlying said floor portion,
- (e) a rectangular ramp member having one edge hingedly connected with one of said top flanges and an opposite edge adapted to engage the floor at one pivoted position of said ramp member and to engage the other of said top flanges at another pivoted position of said ramp member whereby at said first mentioned pivoted position of said ramp member litter may be swept from the floor to said reception chamber and said ramp member closes said reception chamber at said second mentioned pivoted position,
- (f) a pair of rear wheel members rotatably carried by and supporting said housing,

- (g) a pair of front wheels and means swivelingly mounting said front wheels to said housing,
  - (h) said grate member being spaced from said ramp member at said second mentioned pivoted position of said ramp member, and
  - (i) a handle pivotally mounted to said wheel mounting means and operable to be pivoted from a floor engaging position to a position intermediate said ramp member and said grate member whereby at said first mentioned pivotal position of said handle member said handle member resists displacement of the device and at said second mentioned position of said handle member the device is folded into a compact unit for storage or shipping.
13. The device as defined in claim 12 and in which said wheel mounting means comprises
- (a) a steering post mounted on said housing to rotate on an axis substantially normal to the plane of said floor portion,
  - (b) said steering post having one end closely adjacent the plane of said floor portion and an opposite end closely adjacent the plane containing the upper edges of said walls,
  - (c) a cross shaft carried by said steering post adjacent the first mentioned end thereof,
  - (d) said front wheels being rotatably mounted on said cross shaft,

10

- (e) said handle being pivotally carried at the second mentioned end of said steering post.
- 14. The device as defined in claim 13 and including a rod secured to the exterior surface of said floor portion and said rear wheels being rotatably carried on said rod.
- 15. The device as defined in claim 14 and in which said wheels are rotatable on axes substantially parallel to and closely adjacent the plane of said floor portion.
